AIR CONDUCTION HEARING AID HAVING
ADJACENTLY MOUNTED MICROPHONE
AND RECEIVERLawrence G. Weaver, Evanston, Ill., and
Humbert Milani, Gary, Ind.

Application October 25, 1946, Serial No. 705,724

3 Claims. (Cl. 179—107)

1

This invention relates to devices, commonly termed hearing aids, intended for use by persons having defective or impaired hearing, and has to do with devices of this character of the air conduction type.

In hearing aids of the character referred to, a receiver, in the general nature of a telephone receiver and of which there are various types, is mounted on an insert positioned in the ear and having a projection fitting into the auditory canal. The insert has a passage therein opening through the inner end of the projection and communicating with the output of the receiver, so that an air column is provided which is vibrated in accordance with the diaphragm or analogous element of the receiver. Two types of inserts are commonly used. In one type, the insert is molded from an impression taken from the external ear and the outer or entrance portion of the auditory canal, so as to fit snugly in position within the ear. The other type of insert commonly used is the plug type. It is in the form of a short tube, which may have a rubber tip provided with one or more annular vanes or flanges, for insertion into the auditory canal, there being an enlarged head at the outer end of the tube with provision for mounting the receiver thereon.

The receiver is mounted at the outer end or face of the insert and is readily observable. Many persons requiring the use of hearing aids are quite sensitive on the subject and refuse to use such devices, even though needed, since they have a feeling that the receiver and the insert together are quite prominent and attract undesired attention. Since the receiver is mounted on the insert, at the outer end thereof, it is necessary that it be made as small as possible, for two reasons. Firstly, by having the receiver as small as possible, the unsightly projection, at the side of the head, provided by the receiver, is kept as small as possible, rendering it less difficult than would otherwise be the case to persuade persons to wear such devices. Secondly, the receiver, even though as small as practically possible, possesses appreciable weight and is apt to cause displacement or looseness of the insert in the ear. When that occurs, feed back takes place, with resultant squealing which greatly impairs the efficiency of the device. Further, when the receiver is made quite small, it has but little output volume with corresponding loss in efficiency, frequently necessitating operation of the transmitter unit at high power, which may cause objectionable distortion as well as objectionable battery drainage. Also, in constructing a very small receiver, great care is required in

2

making and assembling the parts, which is time consuming and expensive, and it often is extremely difficult, or practically impossible, to construct such a receiver with the precision necessary to assure maximum efficiency.

The receiver, in the known hearing aid devices above referred to, is connected by two fine wires, in the form of a cord, to the terminal contacts of the transmitter unit. That necessitates at least eight contacts, two sets of four each, one set at the receiver end of the cord and one set at the transmitter unit end of the cord. Unless all of the contacts of the respective sets are accurately matched looseness and slippage between the contacts is apt to occur, causing objectionable noise and materially impairing the efficiency of the device. In addition, the wires themselves are a source of trouble and expense. They are necessarily quite fine, for the sake of appearances, and are rather expensive to make. These wires frequently break and have to be replaced, which is an item of appreciable expense to the user, aside from the inconvenience of partial or complete disability of the device due to a broken wire. The wires are, of course, covered with suitable insulation and the rubbing together of the wires causes static which renders it difficult to understand what is being said. Also, rubbing of the wires, or of the cord, against the user's clothing, particularly silk, frequently worn by women, causes objectionable static. When a wire breaks, the ends thereof may be held in loose contact by the enclosing insulation and any slight motion of the cord will cause rubbing together of the ends of the wire, producing noises seriously interfering with hearing. If a wire breaks or becomes exposed adjacent the receiver, it may come in contact with the user's neck, causing repeated burns, the cumulative effect of which may be a serious burn, which may become infected from the wire, and there are numerous cases where that has occurred. In that connection, the transmitter unit commonly is grounded to its enclosing metallic casing, and a circuit can be completed from a broken or exposed wire in contact with the user's body, particularly if perspiration be present, as in warm weather. There is, also, the risk that the wires may become exposed, due to rubbing off of the insulation, and come into contact with each other, causing a short and seriously interfering with the use of the device. Also, in such cases, there is risk that the exposed wires may come in contact with the body and cause burns, even though the transmitter unit is enclosed in a non-conducting casing formed of plastic, as is done in

some devices. Though there are numerous objections to the use of wires from the transmitter unit to the receiver, no one prior to the instant invention has been able to dispense with such wires and they have been accepted as a necessary evil.

The instant invention is directed to the provision of a simple and inexpensive hearing aid device in which the receiver may be disposed remote from the ear, concealed by the user's clothing or apparel, and may be of comparatively large size, and the necessity of providing wires extending from the transmission unit to a receiver adjacent the ear of the user is eliminated. More specifically, under the present invention the receiver is mounted on and operatively connected to the transmitter unit, and the output of the receiver is connected by an enclosed air column, conveniently by means of a tube of appropriate length, to the passage of the ear insert. By eliminating the wires, the numerous difficulties incident to the use of such wires are eliminated, as well as the expense of such wires, in the first instance, and frequent renewal thereof. Also, the contacts associated with such wires and the receiver are greatly reduced, or completely eliminated, correspondingly reducing, or eliminating, difficulties due to the presence of such contacts. By disposing the receiver at the transmitter unit, it may be of comparatively large size, which is conducive to increased accuracy and reduced cost of production. Further, a receiver of large size has much greater output volume than the small size receivers presently used and, even when used with a tube of considerable length, gives much better results, both as to volume and clarity than a small sized receiver mounted directly on the ear insert. A further advantage of the instant invention, is that it enables the use of an ear insert which is practically invisible, or substantially so, thus avoiding the objectionable projection beyond the side of the head, encountered in the prior hearing aid devices, currently used, above referred to. Further objects and advantages of the instant invention will appear from the detail description.

In the drawings:

Figure 1 is a front view of the head and shoulder portions of a man wearing hearing aid means embodying the instant invention, with the head shown in about three-quarters front view;

Figure 2 is an inner side or back view of the transmitter unit, with the removable closure member of the casing omitted, and the receiver mounted thereon in accordance with the instant invention, on an enlarged scale relative to Figure 1, the transmitter unit and associated parts being drawn to actual size thereof;

Figure 3 is an inner side or back view of the upper portion of the transmitter unit of Figure 2, on the same scale as the latter figure, with the upper portion the back wall of the casing removed to show the mounting chassis and associated parts;

Figure 4 is a combined side view, on an enlarged scale, of the receiver and associated parts mounted on the chassis, with the latter shown but fragmentarily, and sectional view of the connector member mounted on the receiver and of the ear insert and the tube connecting it to the connector member;

Figure 5 is an inner face view of the receiver of Figure 4;

Figure 6 is a view similar to Figure 3 but show-

ing a modification with respect to the position and mounting of the receiver;

Figure 7 is a sectional view of the transmitter unit casing, taken substantially on line 7—7 of Figure 6, the chassis and the parts carried thereby being shown in elevation, this view also showing in elevation the connector member mounted on the receiver and, fragmentarily, the tube extending therefrom;

Figure 8 is an outer face view of the receiver and the connector member enclosed within an air sealing member, mounted on the back plate of the chassis, showing a second modification;

Figure 9 is a sectional view taken substantially on line 9—9 of Figure 8, the back plate of the chassis and the receiver and the connector member being shown in elevation;

Figure 10 is an outer face view of the receiver and the connector member mounted on the back plate of the chassis, showing a third modification; and

Figure 11 is a sectional view taken substantially on line 11—11 of Figure 10, certain parts being shown in elevation.

Preferably, though not necessarily, the ear insert used in the instant invention is similar to the insert disclosed in the copending application of Lawrence G. Weaver, Serial No. 634,597, for Hearing aid, filed December 12, 1945. The insert is molded from an impression taken of the external ear and the outer portion of the auditory canal, fits snugly within the ear so as to be effectively retained therein, is preferably formed of a transparent or flesh colored plastic material, and when positioned in the ear is not readily visible. Within the broader aspects of the instant invention, however, any suitable ear insert may be used.

In Figures 1 and 4, there is shown an ear insert 15, preferably similar to the mold insert disclosed in the above identified copending application of Lawrence G. Weaver, as noted. The insert 15 is provided with an inwardly extending tubular projection 16 having therein a passage 17 opening through its inner end. When the insert 15 is properly positioned in the ear, the projection 16 fits snugly into the entrance portion of the auditory canal, into which the inner end of passage 17 opens, and the outer end of passage 17 opens through the then upper portion of insert 15. The insert 15 is then positioned well within the external ear, as shown in Figure 1, so as to be hardly visible and, in fact, cannot easily be detected if formed of transparent or flesh colored material.

A flexible tube 18 has one end portion thereof suitably secured in the outer end portion of passage 17 of ear insert 15. The other end portion of tube 18 is suitably secured in a short duct or passage 19 of a disc shaped connector member 20. An exteriorly knurled ring 21, of brass or other suitable material, is embedded in connector member 20 and defines a bore or recess 22 opening through one side face thereof. This bore 22 opens, at its inner end, into a recess or air chamber 23 formed in connector member 20, which air chamber 23 is connected with tube 18 through an opening or notch 24 in ring 21. A split clamp spring 25 is mounted in ring 21, adjacent the outer end thereof, in an interior circumferential groove 26 formed therein. The clamp spring 25 provides means for attaching the connector member 20 to a receiver, as will be explained presently.

In Figures 2 and 4 there is shown a receiver 28

suitable for use with the hearing aid of the in-

stant invention. This receiver 28 is of known type, and is in the form of a disc provided at one side with a central output stud 29 having a restricted neck. The outer face of receiver 28 is flat, as is the inner face of connector member 20, so that the latter seats flatwise on receiver 28. It will be understood that by pressing connector member 20 toward receiver 28, the stud 29 expands the clamp spring 25 sufficiently to pass therethrough, after which this spring contracts about the restricted neck 31 of stud 29, thereby detachably securing the connector member 20 to receiver 28 seating thereon, as above. As is shown in Figure 4, the depth of the depression in member 20, defined by the bore 22 of ring 21 and by the air chamber 23, is greater than the height of stud 29, providing outward therebeyond the air chamber 23, which opens freely into tube 18. There is thus provided an enclosed air column extending from chamber 23 and the output of receiver 28 to passage 17 of projection or tubular element 16 of the ear insert 15, passage 17 opening into the auditory canal of the ear, when insert 15 is positioned in the ear in the manner described above.

The receiver 28 is provided, at its inner side, with two spaced projections or ribs 32 defining between them a dove-tailed groove. This groove receives a cooperating mounting block 33 suitably secured on a plate 34 of a chassis or mounting frame 35 of a transmitter unit 36. The block 33 is provided with two terminal contact members which cooperate with two similar contact members carried by the receiver 28, for operatively connecting the latter to the transmitter unit 36, when receiver 28 is properly mounted on block 32, as is known.

The connector member 20 may be formed of any suitable material, but preferably is formed of a known plastic and is either transparent or flesh colored. The tube 18 preferably is formed of a suitable plastic such as Vinylite, though it may be formed of rubber, either natural or synthetic, or of any other suitable material, and is preferably either transparent or flesh colored.

The transmitting unit 36 is, as noted, of known type and a brief description thereof will suffice. It comprises a metallic casing 37 in the upper portion of which is mounted a chassis 35 carrying a microphone, amplifying means including electron tubes, means for adjusting the power output of the amplifier, and associated elements. A "B" battery 38 and an "A" battery 39 are appropriately mounted in the lower portion of casing 37, to which they are grounded, these batteries having at one end contact with suitably disposed contact tabs, or fingers, carried by the chassis 35, the latter being secured to the back wall of casing 37 by a screw 40 which serves as a ground connection. The lower section of the back wall of casing 37 is in the form of a removable cover, to give ready access to the batteries and permit of removal and replacement of the chassis 35, as may be required. The front wall of casing 36, at the upper portion thereof, is in the form of a grill work 42 which is disposed in overlying relation to the microphone of the transmitter unit 36. While a transmitter unit, such as that illustrated and above described, by way of example, is preferred, any suitable transmitter unit may be used within the broader aspects of the instant invention.

In the use of the hearing aid device of the instant invention, the insert 15 is properly positioned within the ear and the tube 18 is led up-

ward over the ear thence downward under the wearers clothing to the connector member 20, which is mounted upon the receiver 28 at the back of the transmitter unit 36. The insert 15, when positioned in the ear, cannot easily be detected and the tube 18, which preferably is either transparent or tinted flesh color, does not attract attention, while the receiver is disposed at the back of the transmitter unit 36, which unit may be more or less completely concealed. The device, as a whole, is in no respect conspicuous being, in fact, substantially invisible, and may be worn with comfort. By having the receiver mounted directly on the transmitter unit the tube 18 may be of sufficient length to permit of disposing the transmitter at any desired position on the body, while assuring adequate volume and high clarity of sound transmission through the tube 18, since the receiver 28 may be made of any desired size, as limited only by the size of the unit 36, with the advantages previously mentioned with respect to volume and clarity. By mounting the receiver 28 on the transmitter unit 36, the necessity for wires extending from the transmitter to a receiver positioned adjacent the ear is eliminated, thereby eliminating the numerous difficulties encountered in the use of such wires, above pointed out. If desired, a fine wire may be passed through tube 18 and anchored at its ends to the ear insert 15 and the connector member 20, with a view to resisting tension to which tube 18 might otherwise be subjected in use. Under ordinary conditions, the tube 18 possesses adequate mechanical strength and such a reinforcing wire is not required. Also, if desired, the tube 18 may be of reduced interior diameter at the portion thereof adjacent the ear insert 15, which may be desirable in certain cases as conducive to increased clarity of hearing, though ordinarily that is not required.

In the modification shown in Figures 6 and 7, the mounting block 33 of Figures 3 and 4 is omitted and the receiver 28 is mounted directly on plate 34 of chassis 35, with appropriate operative connection to the transmitter and amplifier unit, as will be readily understood. Preferably the depth of casing 36a, from front to back thereof, is sufficient to accommodate the receiver 28, the back wall of casing 36a having therein an opening 36b of a size to accommodate the connector member 20. By mounting the receiver 28 directly on plate 34 of chassis 35, with direct connection to the transmitter and amplifier unit, the necessity for providing contacts for operatively connecting the receiver to the transmitter unit is eliminated, thereby avoiding the difficulties incurred with respect to such contacts, above mentioned. By disposing the receiver 28 within casing 36a, it is substantially enclosed and guarded thereby against injury, which is advantageous. A screw 40a passes through the back wall of casing 36a and threads into a member associated with plate 34a, providing a ground connection, as before.

When the receiver is positioned on, or closely adjacent to, the transmitter unit there may be, in certain cases, air leakage resulting in squealing and whistling, interfering, to an objectionable extent, with clarity of hearing. Such a leakage may occur, particularly if the connector member 20 is loosely mounted on the receiver 28. In order to guard against leakage between the receiver and the connector member 20, these two members may be enclosed within a container or bag 42, formed of rubber or like material im-

pervious to air, this bag 42 being sealed about the tube 18. If air leakage should occur between the member 20 and receiver 28, the air pulsations or vibrations escaping into the bag 42 will be effectively damped out or killed thereby so that feed back will not occur.

In the modification shown in Figures 10 and 11, the receiver 28a is provided with an exteriorly threaded output stud 29a, on which the connector member 20a is screwed, there being a sealing gasket 44 between this member and the receiver 28a. The gasket 44 is formed of suitable rubber-like material, or any suitable material, assuring an airtight seal between the connector member 20a and the receiver 28a. As will be understood, the member 20a is provided with an air chamber 23a beyond the outer end of stud 29a, communicating by way of a short passage or duct 19a with tube 18. By screwing the connector member 20a into tight seating contact with gasket 44, air leakage between the connector member 20a and the receiver 28a is effectively prevented, thus eliminating risk of feed back and resultant squealing or whistling.

What is claimed is:

1. In hearing aid means, a transmitter unit intended to be positioned remote from the ear comprising a protective casing and a chassis therein, a receiver on said chassis operatively connected to said unit, a connector member defining an air chamber mounted on said receiver with the output of the latter opening into said air chamber, an ear insert having an extension disposed to fit into the auditory canal of the ear when said insert is positioned therein and a passage opening through the inner end of said extension, a flexible tube secured at one end to said connector member opening into said chamber and secured at its other end to said insert opening into said passage, and closure means sealing said receiver and connector member against escape of air therefrom except through said tube.

2. In hearing aid means, a transmitter unit intended to be positioned remote from the ear comprising a protective casing and a chassis therein, a receiver on said chassis operatively

connected to said unit, a connector member defining an air chamber mounted on said receiver with the output of the latter opening into said air chamber, an ear insert having an extension disposed to fit into the auditory canal of the ear when said insert is positioned therein and a passage opening through the inner end of said extension, a flexible tube secured at one end to said connector member opening into said chamber and secured at its other end to said insert opening into said passage, and an airtight member sealed about said receiver and connector member effective for preventing escape of air therefrom except through said tube.

3. In hearing aid means, a transmitter unit intended to be positioned remote from the ear comprising a protective casing and chassis therein, a receiver on said chassis operatively connected to said unit provided at its outer side with an outwardly extending threaded output stud, a connector member defining an air chamber threaded on said stud with the latter opening into said chamber, said connector member seating on said receiver with an airtight seal therebetween, an ear insert having an extension disposed to fit into the auditory canal of the ear when said insert is positioned therein and a passage opening through the inner end of said extension, and a flexible tube secured at one end to said connector member opening into said chamber and secured at its other end to said insert opening into said passage.
